UNITED STATES PATENT OFFICE

146,188

DESIGN FOR A FORK OR OTHER ARTICLE OF FLATWARE

William F. Moran, Meriden, Conn., assignor to
The Ellmore Silver Co., Inc., Meriden, Conn.,
a corporation of Connecticut

Application September 10, 1946, Serial No. 133,234

Term of patent 14 years

(Cl. D54—12)

To all whom it may concern:

Be it known that I, William F. Moran, a citizen
of the United States, residing in the city of
Meriden, county of New Haven, and State of Con-
necticut, have invented a new, original, and orna-
mental Design for a Fork or Other Article of
Flatware, of which the following is a specifica-
tion, reference being had to the accompanying
drawing, forming a part thereof.

Figure 1 is a front elevation of a fork showing

the essential features of my new design in
full lines,

Figure 2 is an enlarged cross-sectional view
taken on the line 2—2 of Figure 1; and

Figure 3 is an enlarged cross-sectional view
taken on the line 3—3 of Figure 1.

I claim:

The ornamental design for a fork or other ar-
ticle of flatware, as shown and described.

WILLIAM F. MORAN.
